ANDRÉ VELUARD, OF PHILADELPHIA, PENNSYLVANIA.

LOOM FOR WEAVING PILE FABRICS.

1,159,436.

Specification of Letters Patent.

Patented Nov. 9, 1915.

Application filed June 3, 1914. Serial No. 842,563.

To all whom it may concern:

Be it known that I, ANDRÉ VELUARD, a citizen of the Republic of France, residing at Philadelphia, in the county of Philadelphia and State of Pennsylvania, have invented certain new and useful Improvements in Looms for Weaving Pile Fabrics, of which the following is a specification.

My invention relates to improvements in looms for weaving and cutting the pile or floats in fabrics having the pile or floats formed of weft threads, wherein the pile or floats are formed over wires which extend in the direction of the warp and wherein knives are employed to cut the pile loops or floats thus formed.

The object of my invention is to provide a novel, simple and efficient means to hold the wires in place and maintain them taut during the operation of the loom; and to provide a novel, simple and efficient cutting means having provision whereby the knives thereof may be readily and separately removed from the machine or placed therein, as occasion may require, without disturbing the wires.

The invention consists of the elements and the combinations of them as will be herein-after fully described and claimed.

In the accompanying drawings, illustrating my invention: Figure 1, is a vertical section, showing parts of a loom having my invention applied thereto. Fig. 2, is a plan view of parts of the breast beam and the pile wires and their supporting and actuating devices. Fig. 3, is a vertical section on line 3—3 of Fig. 2, including a part of a pile wire heddle and the portion of the pile wire extending therethrough. Fig. 4, is a detail showing the eye of the pile-wire heddle. Fig. 5, is a side view of a modification of the knife, its support and adjuncts, certain parts being shown in section. Fig. 6, is a plan view of the knife shown in Fig. 5, its support and a portion of the pile wire. Fig. 7, is a side view of the knife support shown in Fig. 5, showing the knife clamping device in the inoperative position. Fig. 8, is a side view of the knife shown in Fig. 5. Fig. 9, is a section, on line 9—9 of Fig. 5.

Referring first to Figs. 1, 2, 3 and 4 of the drawings, 2 designates the loom frame, 4 the breast beam, 5 the take-up roll for the fabric and 6 the lay. Each end of the lay 6 is connected by a bar or rod 7 to a crank 8 on a shaft 10 which is journaled in the

loom frame and which is rotated in the usual manner to actuate the lay.

The warp threads 11 are raised and lowered by the harness 12, and the woven fabric 13 is wound upon the take up roll 5 in the usual manner during the weaving operation. Extending in the direction of the warp threads 11 is a set of flexible pile wires 14, usually equal in number to the rows of floats or pile tufts to be produced in the fabric. Each pile wire 14 extends freely through an eye 15 in a heddle 16 carried by a heddle frame 17 of usual form; and each pile wire 14 extends forwardly from the eye 15 and rearwardly from the eye 15, as shown. The rearward portion of each wire 14 extends over and around a bar 18, and down through and below an eye in a bar 19 and has a suitable weight or lingo 20 attached to the end thereof. The bars 18 and 19 extend transversely to the wires 14 and are supported by suitable brackets on the frame 2. The forward end of each pile wire 14 is attached to and terminates in a rigid projection 21 which forms, in effect, a continuation of the wire 14; and each projection 21 is formed on a knife-carrying part or member 22 which serves as a means to hold the forward end of the wire in place. Each part or member 22 has a knife 23 formed thereon and provided with a cutting edge facing the pile wires 14 and rising from the forward end of its projection 21 for a purpose hereinafter explained. Each part or member 22 has a groove 24 formed in the bottom thereof which is slidably fitted to a rib 25 formed on and extending longitudinally of a bar 26 which extends transversely to the pile wires 14 and warp threads 11. The members 22 are prevented from being displaced from the rib 25 by a retaining bar 27 having its ends secured to the ends of the bar 26. The bottom face of the retaining bar 27 is adapted to engage the upper faces of the members 22 and retain them in vertical position, and, at the same time, permit lateral movement of the members, so that the pile wires 14 may automatically accommodate themselves to the positions of the rows of pile loops being formed in the fabric.

The bar 26, adjacent to each end thereof is provided with a roller 28 which rests upon a plate 29 projecting from and secured to the breast beam 4, the plate 29 serving to support the end of the bar 26. Each end of

the bar 26 is connected by a link 30 to the upper end of a lever 31 which is fulcrumed, at 32, on the loom frame 2 and has its lower end connected by a rod 33 to a strap 34 which surrounds an eccentric 35 on the shaft 10, whereby, during the rotation of the shaft 10, the members 22 and knives 23 carried thereby will be reciprocated longitudinally or in the direction of the warp threads 11.

The operation is as follows: The interweaving of the warp and weft threads to form the body of the fabric 13 is effected in the usual well known manner; and the heddles 16 are raised and lowered at certain intervals during the weaving operation, to raise and lower the pile wires 14 above and below the shuttle path, similar to the raising and lowering of the warp threads 11, and by the usual well known mechanism of the loom for raising and lowering the warp threads. During the weaving operation, the shuttle is passed across the lay 6 under and over the pile wires 14 and the pile loops or floats are produced over the pile wires 14 in the usual manner. As rapidly as the loops or floats are produced they are beaten up by the lay 6 and pass on to the rigid projections 21 and thence to the cutting edges of the knives 23. As the loops or floats move along the projections 21, during the taking up of the finished fabric by the roll 5, the knives 23 are longitudinally reciprocated by the eccentrics 35 and their connections, as previously explained, and the projections 21 and wires 14 slide back and forth through the rows of advancing pile loops or floats which are cut by the knives 23 as the loops or floats successively meet and pass the cutting edges of the knives.

The pile wires 14 are kept substantially taut by the weights 20 which move up and down and take up the slack which would otherwise occur in the wires 14 during the reciprocations of the members 22 and the raising and lowering of the heddles 16. The fabric with its cut pile loops passes on from the knives 23 and beneath the bar 26 and around the breast beam 4 to the take-up roll 5.

Referring now to the modification shown in Figs. 5, 6, 7, 8 and 9 of the drawings, the member or part 22 and its projection 21 are formed of a single piece of sheet metal bent to form a groove 38 in the top of the projection 21 and to form two side members 36 and a bottom 37 in the forward body portion of the piece of sheet metal, the space 60 between the side members 36 forming a continuation of the groove in the top of the projection 21 and the bottom 37 forming a continuation of the bottom of the groove 38. Between the side members 36 is a removable 65 blade or knife 39 which extends rearwardly

therefrom and into the groove 38 in the projection 21 and has a sharp edge 40 rising from the projection 21 rearwardly of the side members 36, as shown. This knife blade 39 is adapted to be clamped and firmly held in the position shown in Fig. 5 between the side members 36 and within the groove 38 by a clamp member 41 having a top portion 42 and side members 43 extending downwardly therefrom and embracing the side members 36 and pivoted thereto by means of a pin 44 extending transversely therethrough. This clamp member 41 may be moved from the position shown in Fig. 5 to the position shown in Fig. 7 to permit the removal of the knife 39; and it may be moved from the position shown in Fig. 7 to the position shown in Fig. 5 to clamp and hold the knife after it has been inserted into the position shown in Fig. 5, the space between the side members 36 at the free end of the member 41 being such as to force the side members 36 toward each other when the member 41 is moved to the position shown in Fig. 5, thereby firmly clamping the knife blade 39.

The member 22, as shown in Fig. 5, is connected to the bar 26 the same as the member 22 shown in Fig. 3.

I claim:

1. In a loom for weaving pile fabrics having the pile formed of weft threads, the combination of the weaving mechanism, heddles having eyes formed therein, means for raising and lowering the heddles, pile wires extending through the eyes of the heddles and forwardly and rearwardly therefrom in the direction of the warp threads, a support over which the rearward portion of the pile wires extend, a weight attached to the rearward end of each pile wire, to operate the same independently of each other, means to hold the forward ends of the pile wires in place, and knives arranged to cut the pile formed above the pile wires.

2. In a loom for weaving pile fabrics having the pile formed of weft threads, the combination of the weaving mechanism, a heddle, means for raising and lowering the heddle, a pile wire engaged with the heddle and extending forwardly and rearwardly from the heddle in the direction of the warp threads, a part to which the forward end of the pile wire is attached, a knife carried by said part and arranged to cut the pile loops formed above the pile wire, means to reciprocate said part in the direction of the warp threads, and means to draw said pile wire rearwardly and also to permit it to move forwardly when said part is reciprocated.

3. In a loom for weaving pile fabrics having the pile formed of weft threads, the combination of the weaving mechanism, a heddle having an eye formed therein, means for raising and lowering the heddle, a pile

- wire extending through the eye of the hedge-
5 dle and forwardly and rearwardly there-
from in the direction of the warp threads, a
support over which the rearward portion of
the pile wire extends, a weight attached to
10 the rearward end of the pile wire, a part to
which the forward end of the pile wire is
attached, a knife carried by said part and
arranged to cut the pile formed above the
15 pile wire, and means for reciprocating said
part in the direction of the warp threads.
4. In a loom for weaving pile fabrics hav-
ing the pile formed of weft threads, the
20 combination of the weaving mechanism, the
pile wire extending in the direction of the
warp threads, means for raising and lower-
ing the pile wire, a part to which the for-
ward end of the pile wire is connected, a
25 removable knife carried by said part, and
clamping means movable relatively to said
part and arranged to clamp said part and
said knife together.
5. In a loom for weaving pile fabrics hav-
ing the pile formed of weft threads, the
25 combination of the weaving mechanism, a
pile wire extending in the direction of the
warp threads, means for raising and lower-
ing the pile wire, a part to which the for-

ward end of the pile wire is connected, said
part having side members, a removable 30
knife carried by said part and inserted be-
tween the side members thereof, and a
clamp member embracing said side members
and clamping said part and said knife to-
gether. 35

6. In a loom for weaving pile fabrics hav-
ing the pile formed of weft threads the
combination of the weaving mechanism, a
pile wire extending in the direction of the
warp threads, means for raising and lower- 40
ing the pile wire, a part to which the for-
ward end of the pile wire is connected, said
part having a bottom portion and side mem-
bers rising therefrom, a removable knife
carried by said part and inserted between 45
the side members thereof, and a clamp mem-
ber having a top portion and side members
extending downwardly therefrom and em-
bracing the side members of said part and
clamping said part and said knife together. 50

In testimony whereof I affix my signature
in the presence of two witnesses.

ANDRÉ VELUARD.
